HANGER ASSEMBLY FOR INTRAVENOUS BOTTLES OR OTHER DEVICES

James E. Richardson, 4912 Central Ave.,
Indianapolis, Ind. 46205

Filed June 14, 1971, Ser. No. 153,142

Term of patent 14 years

Int. Cl. D8—08

U.S. Cl. D8—246

Fig. 1.

Fig. 2.

Fig. 3.

Fig. 4.

Fig. 5.

FIG. 1 is a front elevational view of a hanger assembly for intravenous bottles or other devices showing my new design.

FIG. 2 is a top plan view thereof.

FIG. 3 is a bottom plan view thereof.

FIG. 4 is a left side elevational view thereof.

FIG. 5 is a rear elevational view thereof.

The appearance of the right-hand side is a mirror image of the left-hand side shown in FIG. 4.

The broken lines are for illustrative purposes only.

I claim:

The ornamental design for a hanger assembly for intravenous bottles or other devices, as shown and described.
